United States Patent Office

Des. 178,330
Patented July 24, 1956

178,330

CAROUSEL

Clara E. Williams, Long Beach, Calif.

Application November 10, 1955, Serial No. 38,860

Term of patent 14 years

(Cl. D34—15)

FIG. 1.

FIG. 2.

The dominant features of my new design are shown in solid lines in the drawing.

I claim:

The ornamental design for a carousel, substantially as shown and described.
